UNITED STATES PATENT OFFICE.

OSCAR WILLIAMS, OF KANSAS CITY, MISSOURI.

COMBINATION BAG TURNER AND COUNTER.

Application filed July 3, 1920. Serial No. 393,939.

To all whom it may concern:

Be it known that I, OSCAR WILLIAMS, a citizen of the United States, residing at Kansas City, in the county of Jackson and 5 State of Missouri, have invented certain new and useful Improvements in Combination Bag Turners and Counters, of which the following is a specification.

My invention relates to a combination bag 10 turner and counter and my object is to provide a simple and efficient apparatus whereby bags can be quickly turned right side out and accurately counted during the turning operation, so that a correct record of all 15 bags turned may be had.

In order that the invention may be fully understood, reference will now be had to the accompanying drawing, in which:

Fig. 1 is a front elevation of the apparatus 20 with a bag in section thereon.

Fig. 2 is a side elevation of the apparatus.

Fig. 3 is an enlarged fragmentary side elevation of one of the standards partly in section.

Fig. 4 is an enlarged cross section on line IV—IV of Fig. 3.

In the manufacture of cotton and other bags, they come from the sewing machine 30 with the seam turned out, and hence must be reversed or turned right side out before being placed on the market. To effect rapid turning of the bags I provide standards 2 and 4 which are adjustably secured to a base 35 6 by bolts 8 and 10, which latter extend through arcuate slots 12 in the base 6 to permit adjustment of the standards, so that their upper ends may be adjusted toward or away from each other to accommodate bags 40 of different widths.

The standard 4 consists of upper and lower sections 14 and 16, respectively, the former of which is provided at its lower portion with a fixed sleeve 18 consisting, 45 preferably, of sheet metal which slidably engages the upper portion of the section 16 which is reinforced by a metallic wear tube 20.

The plunger 22 is fixed at its upper end 50 to the upper standard section 14 by suitable means such as screws 24, which also secure the sleeve 18 in place. The lower portion of the plunger 22 extends freely through guides 24 and 26 secured to the lower section 16. 55 The lower end of the plunger 22 is provided

with a rubber or other cushion 28 for a purpose which will hereinafter appear.

The upper section 14 of the standard 4 is normally held in raised position by a coil spring 30, interposed between the guide 24 and a collar 32 secured to the plunger 22 by suitable means such as a set screw 34. Upward movement of the plunger 22 is limited by a collar 36 adapted to impinge against the guide 24 and adjustably secured to said 60 plunger 22 by suitable means such as a set screw 38. Downward movement of the plunger 22 is restricted by the collar 36 and a collar 40, which latter loosely engages the plunger 22 and rests upon the guide 26. 70

Any well known tally or counter 44 is provided for counting the sacks as they are turned. Said tally 44 is secured by suitable means such as a bracket 46 to the lower portion 16 of the standard 4 and is provided 75 with suitable means such as an element 48 for actuating the counting mechanism. The tally 44 is so positioned as to bring its element 48 beneath the cushion 28, so that each time the plunger 22 makes a downward 80 stroke said cushion 28 will strike said element 48 and move the counting mechanism one step. The cushion 28 prevents damage which would likely occur if the metal plunger 22 came in direct contact with the tally 85 element 48.

In order that the operator may readily know when the plunger 22 has moved down far enough to actuate the tally 44, a suitable signal such as a bell 50 is provided. Said 90 bell 50 is mounted on a bracket 52 secured to the lower portion of the standard 4 by a pivot 56. One end of the clapper 54 is arranged to strike the bell 50 while its opposite end is arranged beneath a lug or pin 58 carried by the collar 37, to actuate the clapper 54 when the plunger 22 moves downwardly. 95

A collar 37 secured to the plunger 22 by a set screw 39 coacts with the collar 36 in limiting the upward movement of said plunger 22. 100

In practice, when a bag such for instance as the bag A, Fig. 1, is to be turned right side out it is grasped at its upper open end C, the margin of which is placed over the upper ends of said standards 2 and 4 and pulled downwardly over said standards, thus turning the bag right side out. The bag A is pulled downwardly with sufficient 105 110

force to overcome the spring 30 and move the upper section 14 of the standard 4 downwardly, together with the plunger 22 until the collar 36 strikes the collar 40. The plunger 22 in its downward movement actuates the tally 44 and the signal bell 50. After the bag has been turned it is released, whereupon the spring 30 moves the section 14 and parts connected thereto upwardly until stopped by the collar 36 impinging against the guide 24. The inverted bag A is then grasped by its closed end B and removed from the standards 2 and 4.

The tension of the spring 30 can be regulated by setting the collar 32 higher or lower on the plunger 22. Should it be necessary or desirable to use the bag turner without operating the tally 44, the collar 40 is locked on the plunger 22 by the set screw 42, 20 to prevent said plunger from descending.

From the foregoing description it will be understood that I have provided an apparatus whereby bags may be turned and counted in one operation and by thus automatically making a record of all bags turned the expense of hiring employees to count the bags, together with mistakes incident to mental counting, is avoided.

While I have shown and described the preferred embodiment of the invention, I do not wish to be restricted to the exact construction shown in the drawings, but reserve the right to make such changes in the construction, combination and arrangement of parts as properly fall within the spirit and scope of the claims.

Having thus described my invention, what I claim and desire to secure by Letters Patent, is:

40. 1. In a bag turning device embodying two standards over which the bags are turned and one of which has a movable portion, mechanism for counting the bags, and

means actuated by the movable portion of the standard for operating said counting mechanism.

2. In a bag turning device embodying two standards over which the bags are turned and one of which has a movable portion, a guide on one portion of the last-mentioned standard for guiding the movable portion, mechanism for counting the bags, and means actuated by the movable portion of the standard for operating said counting mechanism.

3. In a bag turning device embodying two standards over which the bags are turned and one of which has a movable portion, mechanism for counting the bags, means actuated by the movable portion of the standard for operating said counting mechanism, and means for restoring the movable portion of the standard to normal position.

4. In a bag turning device embodying two standards over which the bags are turned and one of which has a movable portion, mechanism for counting the bags, means actuated by the movable portion of the standard for operating said counting mechanism, and means for limiting the movement of the movable portion of the standard.

5. In a bag turning device embodying two standards over which the bags are turned and one of which has a movable portion, mechanism for counting the bags, and a plunger connected to the movable portion of the standard for actuating said counting mechanism.

In testimony whereof I affix my signature, in presence of two witnesses.

OSCAR WILLIAMS.
